STEAM GENERATING APPARATUS

Samuel F. Burnet, Webster Groves, Mo., assignor
to Laclede Christy Clay Products Company, St.
Louis, Mo., a corporation of Missouri

Application April 4, 1932, Serial No. 603,000

2. Claims. (Cl. 122—302)

This invention relates to boilers of the kind that are used in factories and power plants for generating steam.

It is common practice, particularly with small boilers, to arrange a plurality of boilers side by side, so as to produce a so-called "battery boiler" made up of a number of complete steam generating units, each of which comprises a combustion chamber that is separate and distinct from and not in communication with a combustion chamber of another unit. In a battery of two boilers the setting comprises two outer side walls, each of which forms one side wall of a combustion chamber of one unit, and the setting also comprises front and rear walls and a single intermediate wall that is arranged between the two boilers, so as to form a "party" wall that separates or divides the combustion chambers of the respective units.

Modern boiler practice has demonstrated that a single large boiler is more efficient and economical than a plurality of small boilers of equal heating area and equal steam disengaging area, and accordingly, in designing or building a power plant of a certain capacity or rating, it is now the preferred practice to use a single large boiler in place of a plurality of small boilers. Notwithstanding the recognized superiority of a single large boiler over a battery of small boilers, it is not always practicable or feasible from a financial standpoint for the owner of a battery of small boilers to remove the same and replace the battery with a single large boiler. Likewise, in building a new factory or power plant, the owner may have to decide on the use of a plurality of small boilers, instead of a single large boiler, owing to the fact that a plurality of used or second-hand small boilers in excellent condition can usually be purchased at a considerably lower price than a single large boiler.

My invention has for its main object to provide a steam generating apparatus composed of a plurality of small boilers, set side by side, and setting walls and an arch, or arches, combined with said boilers in such a way as to produce a steam generating apparatus that is practically as efficient and economical as a single large boiler of equal heating area and steam disengaging area, but which can be produced at a considerably lower cost than a single large boiler, due to the fact that it is made up of two or more existing small boilers to which parts are added.

Briefly described, my improved steam generating apparatus consists of two or more small boilers set side by side, and each comprising boiler tubes disposed in parallel relation to the side walls of the setting, and drums attached to the ends of the tubes and disposed transversely of the setting, a front wall that forms the front side of a combustion chamber common to all of the small

boilers, side walls for said combustion chamber, and a suspended arch structure (or arch structures, if there are more than two boilers) arranged at the top of the combustion chamber in such a way as to prevent the products of combustion escaping from the combustion chamber at the dividing line of the boilers; and also prevent the products of combustion from injuriously affecting the overhead supporting structure used to support or partly sustain the elevated steam-and-water drums that communicate with the water tubes. The apparatus may comprise any preferred number of small boilers, and any preferred or suitable type of suspended arch may be used to bridge the space or spaces at the top of the combustion chamber between the separate small boilers. I prefer, however, to use a flat arch or arches each of which is made up of refractory blocks or tile suspended from an overhead supporting structure that carries or assists in carrying the elevated drums of the small boilers, said arch or arches extending continuously or unbrokenly from the front wall to the rear wall of the combustion chamber.

I have herein illustrated my invention applied to a pair of Sterling type boilers, but, as previously stated, the number of boilers and the type or kind of boilers is immaterial, so long as the small boilers are provided with tube banks disposed so that the tube banks of the respective boilers extend parallel to each other and also parallel to the side walls of the setting, and transversely disposed drums attached to the boiler tubes and arranged parallel to the front wall of the setting.

Figure 1 of the drawings is a vertical transverse sectional view of a steam generating apparatus constructed in accordance with my invention; and

Figure 2 is a vertical longitudinal sectional view of said apparatus, taken approximately through the longitudinal center of the suspended arch.

In the accompanying drawings which illustrate the preferred form of my invention, A designates the elevated drums or steam-and-water drums of two Sterling type boilers arranged side by side, B designates the mud drums, and C designates tube banks made up of water tubes that constitute the heating surfaces of said boilers. The setting for said boilers comprises two outer walls D that form the opposed side walls of a combustion chamber E that is common to both of the boilers, a front wall F and a rear wall G for said combustion chamber, and a suspended arch H, preferably a flat arch, arranged so as to form part of the roof or top of the combustion chamber E and extending continuously or unbrokenly from the front wall F to the rear wall G of the setting. As shown in the drawings, the tube banks

of the respective boilers are disposed in parallel relation and the water tubes C of said banks extend parallel to the side walls D of the setting. The drums are disposed transversely of the boiler in parallel relation to the front wall of the setting, and the tube banks are disposed at the rear side of the combustion chamber in opposed relation to the front wall F of the setting. The arch H is arranged between the tube banks, in close proximity to the drums A, and consequently, causes the gases in the upper portion of the combustion chamber to be deflected laterally into the upper portions of the tube banks located at the opposite sides of said arch. Said arch is provided with means or is so constructed as to effectively prevent the products of combustion from escaping from the combustion chamber E around the inner ends of the drums A, and also prevent the products of combustion from injuriously affecting the overhead structure that sustains or supports the inner ends of the drums A.

In the apparatus herein illustrated the outer ends of the elevated drums A are supported by the side walls D of the setting or by girders or other suitable supports built into said side walls, and the inner ends of said drums A are sustained by an overhead supporting structure that comprises horizontally-disposed members I that extend longitudinally of the apparatus from the front to the rear of same, and hangars 2 which suspend the members I from horizontally-disposed I-beams 3, which, in turn, are supported by uprights 4 arranged adjacent the front and rear walls of the setting. Obviously, the inner ends of the drums A may be supported in any other preferred or suitable way.

The arch H is herein illustrated as being composed of groups of refractory blocks or tile 5 combined with flanged hangars 6 that are carried by a horizontally-disposed I-beam 7 or other suitable means which is suspended from the members I of the overhead drum supporting structure, previously described, said blocks or tile 5 being of such cross-sectional shape that they co-act with each other to produce an arch H at the top of the combustion chamber, which causes the gases in the central portion of the combustion chamber to be thrown to either side of the arch, into the water tubes of the respective units. Shallow vertical walls 8 made of fire brick, are erected on the arch H so as to surround or partially surround the inner end portions of the drums A and prevent the gases from escaping from the combustion chamber E at the dividing line of the two units, or having an injurious effect on the overhead structure that supports the inner ends of the drums A. The metallic parts of the arch H are protected from excessive heat by the arch tile 5. When my invention is applied to two Sterling type boilers, as herein illustrated, the baffles of the front tube banks of the respective boilers are joined together in such a way, as, for example, by the addition of baffle tile 9, so as to close the space between said front baffles, produced by the removal or elimination of the "party" wall, and thus prevent the gases from short-circuiting from the front pass to the back passes of the apparatus.

A steam generating apparatus of the construction above described, in comparison with a conventional battery boiler of equal heating area and of equal steam disengaging area, has the following advantages:

(1) It has a single combustion chamber or space common to the tubes and the drums of both boilers, in which fuel can be burned more effectively than in two separate and distinct small combustion chambers;

(2) It has a combustion chamber in which a greater quantity of fuel can be burned, due to the fact that the elimination of the "party" wall of the conventional battery boiler and throwing the two combustion chambers into a single combustion chamber, adds considerably to the volume of the combustion chamber;

(3) It has a grate area or burner space which is much larger than the grate area or burner space of the conventional battery boiler, because the space formerly taken up by a "party" wall is now available for additional grates or for oil, gas or other burners; and

(4) It conserves or more effectively utilizes the heat obtained from the burning fuel, as there is no "party" wall or other large mass of refractory material at the dividing line of the two boilers that absorbs considerable heat, especially when the apparatus is first set in operation.

My improved apparatus, in comparison with a large single boiler, has the advantage of being capable of being built or erected at a much lower cost, due, as previously stated, to the fact that a plurality of second-hand small boilers in excellent condition can be purchased on the open market at a much lower price than the cost of a large single boiler.

My improved apparatus has the additional advantage that a conventional "battery" of boilers can be converted into this improved furnace by simply removing the common battery wall and replacing it with the suspended arch arrangement, without moving the boilers or the outer walls of the combustion chamber.

Having thus described my invention, what I claim as new and desire to secure by Letters Patent is:

1. A steam generating apparatus composed of a plurality of small boilers arranged side by side, a setting comprising a front wall and side walls, each of said small boilers comprising tubes that extend parallel to the side walls of the setting and drums attached to said tubes and disposed transversely of the boiler in parallel relation to the front wall of the setting, the tube banks of the respective boilers extending parallel to each other and being disposed at the rear side of the combustion chamber in opposed relation to the front wall of the setting, and a suspended arch structure arranged between the tube banks of adjacent boilers so as to form part of the roof of the combustion chamber and extending from the front wall to the rear wall of the setting, whereby the gases in the upper portion of the combustion chamber will be deflected laterally into the tube banks located at the opposite sides of said arch structure.

2. A steam generating apparatus of the kind described in claim 1, in which each boiler comprises elevated steam and water drums and the arch structure carries walls that are combined with said elevated drums so as to prevent the products of combustion from escaping from the combustion chamber around the inner ends of the elevated steam and water drums.

SAMUEL F. BURNET.
